(57) **CLAIM**

The ornamental design for an effects and controller pedal board, as shown and described.

DESCRIPTION

FIG. 1 is a perspective view of an effects and controller pedal board showing my new design;

FIG. 2 is a side view thereof;

FIG. 3 is a side view thereof from the opposing side as that of FIG. 2;

FIG. 4 is a front view thereof;

FIG. 5 is a rear view thereof;

FIG. 6 is a top view thereof;

FIG. 7 is a bottom view thereof; and,

FIG. 8 is a bottom perspective view thereof.

The broken lines represent the portions of the effects and controller pedal board that form no part of the claimed design.
